A. G. HARTUNG

ATTACHABLE BLADE

Filed July 10, 1925

Inventor
ADALBERTO G. HARTUNG
By Attorney *Maurice*

UNITED STATES PATENT OFFICE.

ADALBERTO GUALTERIO HARTUNG, OF BUENOS AIRES, ARGENTINA.

ATTACHABLE BLADE.

Application filed July 10, 1925. Serial No. 42,813.

This present descriptive specification refers to attachable blades which, through their special shape and construction, can be applied to the different types of non-skid 5 chain devices, such as those at present adopted for automobile tyres, to enable them to cross easily boggy, sandy or snowy places.

As will be seen further on, the blade which constitutes my invention is characterized by 10 the form of the projection which rises from the central part of the plate forming the base.

This projecting blade has an angular notch in one end, which notch is combined 15 with two lateral protuberances, the most salient parts of which remain at a certain distance from the base, and the purpose of which is to hold fast the hook or link of the chain through which the end of the blade has 20 been passed, the chain having previously been placed within the notch.

Although it can be very easily detached, the blade, which is the object of this present 25 application, keeps so firmly attached that it is not liable to be lost, however rough be the work to which it is submitted.

To make this description more clear, drawings are attached as follows:—

Fig. 1 shows in perspective a blade manufactured in accordance with my invention.

Fig. 2 is a drawing in plan of one of said blades fitted to an ordinary chain.

As can be seen in these drawings, the blade (1) rises in the centre of the base, 35 the whole being made of one single sheet,

stamped and suitably drawn out; or it may be cast, forged or manufactured by any suitable method. The lateral protuberances (3) are formed in the blade, and these are to hold the link through which the blade is 40 passed. The blade has a notch made in combination with these protuberances, by means of which the hooking link (4) can easily be attached, which link usually joins the circumferential chains with the axial 45 ones.

Having thus described and specified the character of my invention, and the method of applying it, I claim as my exclusive invention and property:—

1. An attachment for non-skid chains, comprising a plate having a blade projecting centrally from its outer face, said blade having a notch in one end and provided adjacent its other end with a projection on 50 each side, the blade being adapted to be passed through a link of a transverse chain with the projections above the link and with a circumferential chain lying in the notch thereof.

2. An attachment for non-skid chains, comprising a plate having a blade projecting from its outer face, said blade having an angular notch in one end and provided adjacent its other end with projections on its 55 sides, the projections gradually increasing in thickness inwardly and terminating a short distance from the plate.

ADALBERTO GUALTERIO HARTUNG.
